US0D1031705S

(12) **United States Design Patent** (10) **Patent No.:** **US D1,031,705 S**
(45) **Date of Patent:** **** Jun. 18, 2024**

(54) **STAND FOR A TELEVISION RECEIVER**

(71) Applicant: **LG ELECTRONICS INC.**, Seoul (KR)

(72) Inventors: **Sungyong Park**, Seoul (KR); **Hyojin Won**, Seoul (KR); **Younsoo Kim**, Seoul (KR); **Min Kim**, Seoul (KR)

(73) Assignee: **LG ELECTRONICS INC.**, Seoul (KR)

(**) Term: **15 Years**

(21) Appl. No.: **35/517,129**

(22) Filed: **Nov. 7, 2022**

(80) **Hague Agreement Data**

Int. Filing Date: **Nov. 7, 2022**

Int. Reg. No.: **DM/225264**

Int. Reg. Date: **Nov. 7, 2022**

Int. Reg. Pub. Date: **May 12, 2023**

(30) **Foreign Application Priority Data**

Jun. 23, 2022 (KR) 30-2022-0025177

(57) **CLAIM**

The ornamental design for a stand for a television receiver, as shown and described.

DESCRIPTION

1. Stand for television receiver

1.1 : Perspective

1.2 : Rear perspective view

1.3 : Front

1.4 : Back

1.5 : Left

1.6 : Top

1.7 : Bottom

1.8 : Reference

The broken lines indicate portions of the article that form no part of the claimed design; the broken line showing of the television receiver is provided for the purpose of illustrating environmental structure and form no part of the claimed design; the right side view is omitted because it is a mirror image of the left side view; reproduction 1.8 is a rear perspective view in which a television receiver is combined with the claimed design.

1 Claim, 8 Drawing Sheets
